W. J. LAFFEY

BULKHEAD FOR FREIGHT CARS

Filed Sept. 8, 1922

Patented June 24, 1924.

1,499,229

UNITED STATES PATENT OFFICE.

WILLIAM J. LAFFEY, OF MEMPHIS, TENNESSEE.

BULKHEAD FOR FREIGHT CARS.

Application filed September 8, 1922. Serial No. 586,945.

To all whom it may concern:

Be it known that I, WILLIAM J. LAFFEY, a citizen of the United States, residing at Memphis, in the county of Shelby and State 5 of Tennessee, have invented certain new and useful Improvements in Bulkheads for Freight Cars, of which the following is a specification.

My said invention relates to bulkheads for 10 freight cars and it is an object thereof to provide a bulkhead which can be moved lengthwise of the car and set up at different points in accordance with the nature of the freight to be held in place.

Another object is to provide bracing means 15 for supporting the bulkhead rigidly in adjusted position.

A further object of the invention is to provide means on the car for holding the 20 bulkhead out of the way when not in use.

Referring to the accompanying drawings which are made a part hereof and on which similar reference characters indicate similar parts,

Figure 1 is a perspective of a part of a freight car with parts broken away to show the different positions of the bulkheads,

Figure 2 a detail showing the bracing means, and

Figure 3 shows a modified arrangement of the bulkhead.

In the drawings reference character 10 indicates the floor of a freight car having sides 11. The floor of the car is provided 35 with a plurality of transverse rows of recesses each having a cover 12 with a swinging door 13. Other recesses arranged in transverse rows spaced from those of the first series are provided with slotted covers

14. Bulkheads 15 are adapted to be stationed transversely of the car and have upright stiffeners 16 attached thereto which are bent at their lower ends as indicated at 17. These uprights are adapted to pass at

40 their lower ends through openings in the covers 14 and have a hooked engagement with said covers.

Near the upper end of each upright is a 45 bent rod or pin 18 forming a pivot for a brace 19 which at its lower end has a head 20 spaced from the body of the brace by a reduced portion 21. At the outer lower corner of each bulkhead an eye 22 is secured thereto by a swivel connection, this eye em- 50 bracing a rod 23 extending along the lower

corner of the car. A second series of openings for engagement by the uprights is indicated at 24 and a second series of openings for engagement by the lower ends of the braces is indicated at 25.

In the operation of the device it will be seen that the doors 13 may be opened after which the heads of the braces may be disengaged from the covers 12. The braces may then be swung upward on their pivots 18 and this permits the bulkhead to be swung backward to disengage the lower end of the uprights from the slotted covers 14, such movement being permitted by the swiveled connection between the bulkhead and the eye 22. The bulkhead is now connected to the car only by the eye 22 which is slidable on the rod 23 and therefore it may be moved to the next series of floor openings of which there may be several as will be understood. Such an additional position of the bulkhead is indicated in dotted lines at 26. Should the bulkhead not be needed it may be moved to one side against the side wall of the car, as indicated at Figure 1. 60 In thus arranging it the braces are swung on their pivots to lie flat against the bulkhead between it and the side of the car and project up or down as may be convenient, the bulkhead being tipped over on one side 65 and a stake 27 being inserted between the bulkhead and the rod 23 to hold the bulkhead in place. This stake is preferably pivotally fastened to the side of the car at 28 to form a holding means for the bulkhead 70 when desired.

Figure 3 shows a modified construction in which the bulkhead 15' is not movable along the floor of the car but is supported on a removable floor section 29. The upright stiffeners 16' are the same as in the preferred form and have a hooked engagement with plates 14'. The braces 30 are pivoted to the floor at 31 in recesses underneath the section 29. When the bulkhead is not in use 95 it occupies a collapsed position indicated in dotted lines at 32 in Figure 3. When it is to be used the floor section is lifted, the bulkhead is raised out of the recess and the floor section is returned to its position, the uprights being caused to engage with openings in the plates 14' during such movement of the floor section.

It will be obvious to those skilled in the art that my device may be modified in vari- 110

ous ways without departing from the scope of the invention as indicated in the appended claims.

Having thus fully described my said invention, what I claim as new and desire to secure by Letters Patent, is:

1. A transversely extending bulkhead for freight cars comprising an upright body member, stiffeners attached thereto and adapted to extend into openings in the floor and braces pivotally secured to the rear side of the bulkheads and engaging openings in the floor, substantially as set forth.

2. A freight car having spaced transversely arranged sets of openings in its floor, bulkheads having means at their lower ends adapted to engage certain of said sets of openings and braces on said bulkheads adapted to engage other sets of said openings, substantially as set forth.

3. A freight car having a transversely extending bulkhead, a brace pivoted to the bulkhead, a rod extending along the lower corner of the freight car, and pivotal connections between said rod and said bulkhead whereby the bulkhead may be caused to lie against the side wall of the car with the brace between said bulkhead and said wall, substantially as set forth.

4. A freight car having a transversely extending bulkhead, a rod extending along the lower corner of the freight car, such bulkhead having pivotal connection with said rod whereby the bulkhead may be caused to lie against the side wall of the car, and means secured to the side of the freight car for locking the bulkhead in such position, substantially as set forth.

5. A freight car having openings in its floor, metallic plates covering the same, certain of said plates having slots extending

transversely of the car, a transversely extending bulkhead, upright stiffeners on the bulkhead adapted at their lower ends to engage said slots and braces connected to the bulkheads at one end and engaging the floor at the other, substantially as set forth.

6. In a freight car, a transversely extending bulkhead having means at its lower edge for engaging the floor of the car, a brace pivoted thereto near its upper edge, said freight car having openings in its floor, heads on the braces adapted to project into said openings, and means for engaging over said heads to hold them in place, substantially as set forth.

7. A freight car having transversely extending bulkheads, braces extending rearwardly therefrom into engagement with the floor, said bulkheads pivotally connected at one corner to the freight car whereby they may be laid flat against the wall of the car and said braces pivotally connected to the bulkheads to lie between the bulkhead and the side of the car, substantially as set forth.

8. A bulkhead for freight cars comprising an upright body member, stiffeners therefor, means for securing said stiffeners releasably to the floor of the car, and inclined braces extending rearwardly from the bulkhead and releasably secured to the floor of the car, substantially as set forth.

In witness whereof, I have hereunto set my hand and seal at Memphis, Tennessee, this 7th day of August, A. D. nineteen hundred and twenty-two.

WILLIAM J. LAFFEY. [L.S.]

Witnesses:

JOHN W. FARLEY,
F. M. BAILEY.
